UNITED STATES PATENT OFFICE

2,358,054

ORTHOGRAPHIC PROJECTION STAND

Frederick J. Bryant, Auburn, Maine

Application January 14, 1944, Serial No. 518,287

4 Claims. (Cl. 248—125)

This invention relates to an orthographic projection stand and it is one object to provide a stand adapted to hold an object while a draftsman or artist is making a sketch or drawing thereof, the device being of such construction that a platform constituting an element thereof may be shifted vertically to adjusted positions and a carrier upon which the object is directly mounted turned to angularly adjusted positions. It will thus be seen that the artist or draftsman may view the object from the front, from a position above the same, or from one side or the other, according to the views desired when making a sketch or drawing of the object.

Another object of the invention is to so form a bracket carrying the shelf or table that it may be easily shifted vertically along a standard and be frictionally held in adjusted position.

Another object of the invention is to provide a shelf or table which is mounted upon a portion of the bracket for turning adjustment on a horizontal plane, the object to be drawn being carried by a prong extending upwardly from a member mounted for universal turning and tilting adjustment so that the artist or draftsman may accurately adjust the same after the bracket has been shifted upwardly and the platform turned to approximately the desired position.

Another object of the invention is to so mount the universally adjustable carrier that access may be readily had to a set screw and the screw tightened to create binding engagement with the carrier and frictionally hold the carrier in an angularly adjusted position.

Another object of the invention is to provide a device of this character which is simple in construction, easy to operate, and capable of being manufactured at small cost.

In the accompanying drawings:

Fig. 1 is a view showing the stand inside elevation, a portion of its base being in section.

Fig. 2 is a view on the line 2—2 of Fig. 1.

Fig. 3 is a view on the line 3—3 of Fig. 1.

Fig. 4 is a fragmentary view on an enlarged scale, showing the bracket, a portion of the platform, and a portion of the standard, the view being taken on the line 4—4 of Fig. 2 and being partially in elevation and partially in section.

Fig. 5 is a view on the line 5—5 of Fig. 4.

Fig. 6 is a view taken at right angles to Fig. 4.

Fig. 7 is a view looking at the upper face of the table carrier.

Fig. 8 is a perspective view of a disc for compressing packing in the sleeve of Fig. 4.

Fig. 9 is a fragmentary sectional view on the line 9—9 of Fig. 2.

Fig. 10 is a view on the line 10—10 of Fig. 9.

Fig. 11 is a view looking at the under face of the table or platform.

This improved orthographic projection stand

has a post or standard 1 formed from a metal rod of suitable length and rectangular in cross section. This rod has its lower end portion formed with a depending threaded stem 2 which passes through an opening at the top of a base 3 and is secured by a nut 4 screwed on its lower end, as shown in Fig. 1. The base is hollow and of such size that the standard will be supported upright and prevented from tilting over.

A bracket 5 is carried by the standard for vertical adjustment thereon and has a sleeve or pocket 6 which is closed at its upper end by a head or wall 7 and open at its lower end for insertion of packing 8 and a disc 9. Ears 10 are formed at opposite sides of the disc and formed with threaded openings 11 to receive screws 12 by means of which the disc is shifted upwardly to compress the packing in the pocket or sleeve for frictional binding engagement with the standard. An opening 13 is formed centrally of the disc to accommodate the standard and at its opposite sides the annular wall of the pocket is formed with vertically extending recesses 14 to receive the ears 10 and guide vertical movement 25 of the disc. Since the screws pass downwardly through the pocket and their heads bear against the top wall 7 thereof, the screws may be very easily turned with a screw driver to adjust the disc and apply additional compression to the packing when necessary.

An arm 15, braced by a depending web 16, extends laterally from the sleeve 6 at one side thereof and from the other side of the sleeve extends a finger 17 which is out of alignment with the arm 15 and terminates in an upwardly disposed seat to receive a person's finger. By this arrangement of parts, a person may engage his fingers under the sleeve to shift the bracket 5 upwardly to an adjusted position, where it will be held by frictional grip of the packing and by applying a finger to the seat 18 and applying pressure, the bracket may be easily shifted downwardly along the standard to adjusted positions. Since the finger-receiving seat 18 is offset with respect to the sleeve, the bracket may be readily shifted downwardly and when pressure upon the seat is removed, binding grip of the packing will hold the bracket against accidental longitudinal movement upon the standard. The weight of the arm and the table 19 carried thereby causes canting movement to be imparted to the sleeve and assists in creating binding engagement with the standard and when downward pressure is applied to the outer end of the finger 17 it tends to straighten the sleeve about the standard and allow it to be slid downwardly very easily.

The table or platform 19 is formed of wood or other suitable material and is preferably oblong as shown in Figs. 2 and 3. The platform carries a metal disc 20 which is secured to its under face

by screws 21 passed through openings 22 near the periphery of the disc and this disc is held in position upon a companion disc 23 at the outer end of arm 15 by a bolt 24 which passes through an unthreaded opening 25 at the center of the disc 20 and is screwed into a threaded opening 26 at the center of the disc 23. The head of the bolt or screw is received in a recess 27 formed in the under face of the table to accommodate the same. In order to limit turning of the disc 20 and the table or platform relative to the disc 23, there has been provided a pin 28 carried by the disc 23 and projecting upwardly into a slot 29 formed in the disc 20. This slot is arcuate and concentric to the opening 25 and only allows limited turning of the disc.

When the device is in use, an object to be drawn is affixed to a prong or carrier 30, as indicated by dotted lines in Figs. 1 and 2. The prong projects from a spherical block 31 through an opening 32 at the top of a casing 33 which is of frusto-conical shape and secured upon the platform by screws 34. The casing 33 is located centrally of the platform, as shown in Fig. 2, but the disc 20 is off center, as shown in Fig. 3, in order that the block 31 and the seat 35 upon which it rests will be disposed out of alignment with the screw 24. A set screw 36 is threaded upwardly through an opening in the platform and this opening 37 has an enlarged lower portion which is aligned with an opening 38 which moves into and out of registry with a companion opening 39 formed in the disc 23 so that by passing a screw driver upwardly through the openings 38 and 39, the screw may be adjusted to lift the seat 35 into position for binding engagement with the spherical block 31. It will thus be seen that the prong 30 may be allowed turning and universal tilting movement to adjusted positions. Therefore, when the device is in use, the object may be disposed face toward a person and the bracket shifted upwardly to a level with his eyes while a front view is being drawn and then the platform turned to present a side toward the front so that a side view may be drawn. After the side view has been drawn at a side of the front view, the bracket 5 is shifted downwardly by pressure applied to the outer end of the finger 17 and when the object is in position permitting a view of its top, a top view is drawn back of the front view. The views may then be combined in the usual manner to produce a composite figure and the top view, side view, and front view also used individually if so desired.

Having thus described the invention, what is claimed is:

1. A drawing apparatus of the character described comprising a standard, a support shiftable vertically along said standard to adjusted positions, compressible means carried by said support for gripping said standard and frictionally holding the support in an adjusted position, a platform carried by said support and disposed in spaced relation to one side of the standard, a holder for an article to be drawn carried by said platform, the weight of the platform tending to cant the support transversely of the standard into position for gripping the support, and a member extending laterally from the support at the opposite side thereof from the plat-

form and having a finger-engaging element at its outer end whereby downward pressure may be applied thereto to shift the support downwardly along the standard.

- 5 2. A drawing apparatus of the character described comprising a standard, a support shiftable vertically along said standard to adjusted positions including a sleeve about said standard having a wall at its upper end formed with an opening through which the standard passes, packing in said sleeve, a plate in the sleeve under the packing, screws passing vertically through the sleeve with their lower portions threaded through the plate for shifting the plate upwardly and compressing the packing for gripping engagement with the standard to frictionally hold the sleeve in adjusted position upon the standard, an arm extending from one side of said sleeve, a platform mounted at the outer end of said arm in a horizontal position, a holder for an object carried by said platform, and a finger extending from the sleeve at the opposite side thereof from the arm and formed at its outer end with a finger-receiving seat whereby downward pressure may be applied to the finger to shift the sleeve downwardly along the standard.
- 10 3. A drawing apparatus of the character described comprising a standard, a support shiftable vertically along said standard to adjusted positions including a sleeve about said standard having an arm extending from one side, compressible means carried in said sleeve for frictionally gripping the standard and holding the sleeve in a set position thereon, a disc at the outer end of said arm in a horizontal plane, a companion disc resting upon the first disc, a pin loosely passing through the center of the upper disc and screwed into a threaded opening in the lower disc, said pin serving as a pivot for the upper disc, a platform firmly mounted upon the upper disc to turn therewith about the pin and having its under face formed with a pocket into which the head of the screw fits, and a holder for an object carried by said platform in eccentric relation to the screw.

- 15 4. A drawing apparatus of the character described comprising a standard, a support shiftable vertically along said standard to adjusted positions and having an arm extending from one side, means carried by said support for gripping the standard and holding the support in a set position thereon, a disc at the outer end of said arm in a horizontal plane, a companion disc resting upon the first disc, a pin passing through the center of the upper disc and engaged with the lower disc to mount the upper disc for turning adjustment in a vertical plane, a shell resting on said platform over the discs, a seat enclosed by said shell, a spherical block resting on said seat and carrying a spike projecting upwardly through an opening in the top of the shell, the platform being formed with a threaded opening under the seat, a screw engaged through the threaded opening with its upper end engaging the under face of the seat, and said discs being formed with openings for registering and permitting access to the lower end of the screw whereby the screw may be tightened and frictionally hold the block against movement.

FREDERICK J. BRYANT.
